UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

FLAT-BED WEB-PRINTING PRESS.

No. 856,758.

Specification of Letters Patent.

Patented June 11, 1907.

Application filed August 22, 1906. Serial No. 331,602.

To all whom it may concern:

Be it known that I, HENRY F. BECHMAN, of Battle Creek, in the county of Calhoun and State of Michigan, have invented certain new and useful Improvements in Flat-Bed Web-Printing Presses; and I hereby declare that the following is a full, clear, and exact description thereof, reference being had to the accompanying drawings, which form part of this specification.

This invention is an improvement in flat bed reciprocating cylinder presses of the "duplex type" and its object is to provide a press of this character capable of printing sixteen pages or less at each operation in one color, and eight pages or less in multi-color, and specifically is an improvement upon the sixteen page "duplex" press shown in my application for patent filed August 27, 1906, Serial No. 332,169.

The objects of the present invention are to enable both sets of equalizing devices and both sets of feeding and delivering devices to be arranged at one end of the press so that the feeding and delivering mechanisms can be directly intergeared and all the looping rollers or "equalizers" can be mounted on one frame and operated directly by the same set of cams; and to provide web guides whereby webs may be threaded through the press in a novel manner in order to be perfected in one color, or to be perfected in multi-color.

The invention will be fully understood from the accompanying drawings and summarized in the claims following the description of the machine illustrated in the drawings.

In said drawings—Figure 1 is a diagrammatical longitudinal sectional elevation of the machine showing the arrangement of the printing, feeding, looping and delivering mechanisms, and a mode of threading two webs through the press to be perfected in one color. Fig. 2 is a similar view showing a mode of threading one web through the press to be perfected in multi-color.

The press has four type beds 1, 1^a, 2, 2^a, which are arranged in two parallel planes, the beds 1 and 2 being arranged end to end in one plane and the beds 1^a, 2^a being arranged end to end directly over and parallel with the beds 1 and 2, respectively.

Cylinders 1^b, 1^c, 2^b, 2^c, co-act with the respective beds 1, 1^a, 2, 2^a and are rolled back and forth thereover by suitable mechanism as shown in my aforesaid application, for instance, the same being well understood and needing no particular description herein.

The arrangement of the several web manipulating mechanisms can be more readily traced by following the course of the webs through the press as indicated in the drawings.

Referring to Fig. 1, web W is led in from roll W' under guide 3^a, to the feeding-in rolls 4, thence up over looping roller 5^a, down under guide roller 3^b, over guide 3^c, between bed 1, and cylinder 1^b, over guides 3^d and 3^e, down under guide 3^f, back below bed 2 to guide 3^g, up over guide 3^h, to guide 3ⁱ then between bed 2^a and cylinder 2^c over guide 3^j, then to guide 3^k, then to guides 3^l and 3^m, down under looping roller 5^a, and up to delivery mechanism 6, where it is split longitudinally and one-half w' of the web passes directly over guide roller 3° to the former or folder F, at the end of the machine, and the other half w^o of the web is turned under deflector 3^p, thence under guide 3^q, and over guide 3^r to the folder F, the halves of the web being assembled at the folder. This assembling being old needs no particular description.

Another web W² is led in from a roll W³ under guide 7^a through a feeding mechanism 4^a (similar to the feeding mechanism 4,) up over looping roller 5^b, down under guide 7^b, over guide 7^c, between bed 1^a and cylinder 1^c, up over guide 7^d to and over guide 7^e, 90 and down under guide 7^f, back under bed 2, (passing between the latter and web W) to a guide 7^g up over guide 7^h, back over guide 7ⁱ, between bed 2 and cylinder 2^b to guide 7^j to guide 7^k, up over guide 7^l to guide 7^m, then down under looping roller 5^c, over a guide 7ⁿ, to delivery mechanism 6^a, where the web may be slit and one-half w³ of it passes direct over a guide 7^o, to the folder F, while the other half of web w⁴ is passed under a deflector 7^p, under guide 7^q and over guide 7^r to the former, thus the two halves of web W² are assembled with the two halves of web W at the former and folded together.

The guide rollers 3^c and 3^d travel with cylinder 1^b; similarly rollers 7^c, 7^d travel with

cylinder 1^c; rollers 3^j and 3ⁱ travel with cylinder 2^c and rollers 7ⁱ, 7^j travel with cylinder 2^b. This arrangement of cylinders and double guides being such as are employed in the duplex press.

The feeding mechanism 4, is preferably constructed as in the duplex press and as shown in patent to J. L. Cox, No. 478,503, dated July 5, 1892, and patent No. 680,111, 10 August 6, 1901, and the feeding devices 4 and 4^a are similarly constructed and they should be driven in unison, so that the webs will be fed into the press uniformly. The delivering devices 6 and 6^a are also preferably constructed 15 as described in said patents, and are intergeared with each other and with the feeding mechanisms 4 and 4^a so that the webs will be fed out of the press as fast as they are fed thereto.

20 The looping rollers or "equalizers" 5^d, 5^a, 5^b, 5^c are adapted to take up the slack of the web during impressions and to shift the web forward after impressions, substantially described in said patents, wherein, however, 25 but one set of looping rollers is employed; whereas in the present case, two sets of looping rollers are employed with the two webs. Both sets of looping rollers 5^d, 5^a, 5^b, 5^c are mounted on the same supports 5, which are 30 operated by means of lever 5^f and cam 5^g operated in unison with the feed and delivering mechanism substantially described in patent No. 501,456, May 11, 1893, so that the looping devices form virtually but one mechanism and operate as one. The operation 35 of the press briefly stated, is as follows:

Each web is constantly fed into and delivered from the press. The portion between the feed and delivery mechanisms is 40 momentarily stopped by the vibrating action of the looping rollers during each printing period. The impression cylinders are rolled over the beds and make impressions from the type forms on the beds, thereafter the looping rollers shift the web forward, the proper 45 length of web being moved through the press after each impression, as in the well known duplex press, and as described in said Cox patent. In the Cox duplex press the product 50 is only eight pages, because but two beds and cylinders and one set of feeding, looping and delivering mechanisms are employed. In my press I employ four beds and cylinders and two sets of feeding, looping and delivering 55 mechanisms. It will be noted that in my press the web W is not perfected in the superposed bed, but is printed on one side by a bed in one plane and on the other side by an adjacent bed in another plane, and that 60 the web W² in the illustration shown in Fig. 1, is printed within a large loop of the web W, and that the web W is passed between beds 1, 1^a under bed 2, and over bed 2^a while the web W² passes over both bed 1, 1^a,

under both beds 2, 2^a and again under bed 2^a. 65 Both webs are handled by one set of cams 5^g. Preferably the guide rollers 3^f, 7^f, 3^g, 7^g, 3^h, 7^h, 3ⁱ and 7^k and 3^e and 7^e are positively rotated during the operation of the press to assist in forwarding the webs thereover.

70 When the press is threaded as shown in Fig. 1, and both webs are full width a sixteen page paper can be produced. By using one wide and one narrow web, a paper of ten, twelve or fourteen pages can be produced. 75 When printing but eight pages or less, only one web need be used and the other beds and cylinders can be put out of operation if desired.

When it is desired to print in multi-color 80 a single web may be used, for instance, a web W can be led in over guide 3^a through feeding devices 4, over looper 5^a, under guide 3^b over guide 3^c between bed 1, and cylinder 1^b over guide 3^d and thence to guide 7^j between bed 85 2, and cylinder 2^b, over guide 7ⁱ, back under guide 7^h, up over guide 3^h to guide 3ⁱ, down between cylinder 2^c and bed 2^a, up over guide 3^j back to guide 7^d down between cylinder 1^c and bed 1^a, over guide 7^e, under 90 guide 7^b then up over guide 7^m, down under looper 5^c, over guide 7ⁿ, to delivery 6^a and thence out to the folder as above described. In this manner a web may be perfected in one color on beds 1, 2^a, and perfected in 95 multi-color on beds 2, 1^a. The press can be threaded in various other modes if desired, which is unnecessary to describe herein.

Some of the advantages of the present construction are the shortening of the press, because the feeding, looping and delivering devices all being at one end of the press as the two beds 1 and 2 are arranged end to end in one plane, and beds 1^a, 2^a, are arranged end to end in another plane parallel with the beds 100 1 and 2, the four beds can be brought close together and at the same time kept near the floor, hence less length of web will be required in the printing mechanism; also the feeding and delivering mechanisms being 105 thus brought close together are very compact and can be driven with less lost motion therebetween; also the looping rollers can all be actuated from a single set of cams; the capacity of such press is double that of an ordinary duplex press.

Having described my invention what I claim as new and desire to secure by Letters Patent is:

1. In a web printing press, the combination of four type beds and co-acting impression cylinders, said beds being arranged in two planes, two beds end to end in each plane and the beds in one plane being parallel with the beds in the other plane,—with a 120 set of web feeding, looping and delivering mechanisms at one end of the press, and web guides whereby one or more webs can be di- 125

- rected between the beds and cylinders, substantially as described.
2. In a web printing press, the combination of four type beds and co-acting impression cylinders, said beds being arranged in two planes, two beds end to end in each plane and the beds in one plane being parallel with the beds in the underlying plane— with two sets of web feeding, and delivering mechanisms and a single web looping mechanism at one end of the press, a folder, and web guides whereby a web may be directed through the press to the folder, substantially as described.
3. In a web printing press, the combination of four type beds and co-acting impression cylinders, said beds being arranged in two planes, two beds in each plane and the beds in one plane being parallel with the beds in the other plane, web feeding, and web delivering mechanisms, a single web-looping mechanism, and web guides whereby webs may be directed through the press, each web being printed on one side by a bed and cylinder near the feeding and delivering mechanisms and perfected by a bed and cylinder remote from the feeding mechanisms.
4. In a web printing press, the combination of four type beds and co-acting impression cylinders, said beds being arranged in two planes, two beds end to end in each plane and the beds in one plane being parallel with the beds in the other plane; with two web feeding, and delivering mechanisms at one end of the press a single web-looping mechanism adapted to handle all the webs, and web guides whereby a web or webs may be directed through the press, so that each web may be printed on one side by a bed and cylinder near the feeding and delivering mechanisms and perfected by a bed and cylinder remote from the feeding mechanisms.
5. In a printing press, the combination of four printing couples arranged in two planes, the printing couples in each plane being end to end and closely adjacent, each couple comprising a stationary bed and a reciprocating impression cylinder, web feeding mechanisms, web delivering mechanisms and a single web looping mechanism at one end of the press, and web guides whereby a web may be carried from the feeding mechanism through two of the printing couples not in the same plane, and whereby a second web may be directed through the remaining printing couples; with a folder adjacent the feeding and delivering mechanisms, and means for di-
- recting the webs from the delivering mechanisms into the folder.
6. In a printing press, the combination of four printing couples arranged in two planes, each couple comprising a stationary bed and a reciprocating impression cylinder the beds in each plane being arranged end to end, two sets of web feeding mechanisms, two sets of web delivering mechanisms and a single web looping mechanism at one end of the press, and web guides whereby a web may be carried from one feeding mechanism through two of the printing couples not in the same plane, and whereby a second web may be directed through the remaining printing couples; with means for operating the said feeding and delivery mechanisms in unison, the said looping mechanism being operated by a single cam; a folder adjacent the feeding and delivering mechanisms, and means for directing the webs from the delivering mechanisms into the folder.
7. In a printing press, the combination of two pairs of parallel beds arranged end to end in a main frame, two pairs of reciprocating impression cylinders co-acting with the beds, web-feeding and delivering mechanism, and web-looping mechanism, means for directing a web of paper between the uppermost bed and cylinder in one pair to be printed, and then between the lowermost bed and cylinder in the other pair to be perfected, and means for directing a second web between the lower bed and cylinder of the first pair, and the upper bed and cylinder of the second pair to be perfected.
8. In a printing press, the combination of four printing couples arranged in two planes, each couple comprising a stationary bed and a reciprocating impression cylinder, two sets of web feeding mechanisms, two sets of web delivering mechanisms, and a single web looping mechanism at one end of the press, and web guides whereby a web may be carried from one feeding mechanism through two of the printing couples not in the same plane, and whereby a second web may be directed through the remaining printing couples, substantially as described.

In testimony that I claim the foregoing as my own, I affix my signature in presence of two witnesses.

HENRY F. BECHMAN.

In presence of—

F. W. DUNNING,
CHAS. A. GRAMES.
